UNITED STATES PATENT OFFICE.

FREDRICK C. STARKE AND PETER J. CROWLEY, OF MILWAUKEE, WIS.

DERRICK.

SPECIFICATION forming part of Letters Patent No. 268,957, dated December 12, 1882.

Application filed October 11, 1882. (No model.)

To all whom it may concern:

Be it known that we, FREDRICK C. STARKE and PETER J. CROWLEY, both of Milwaukee, in the county of Milwaukee, and in the State 5 of Wisconsin, have invented certain new and useful Improvements in Derricks; and we do hereby declare that the following is a full, clear, and exact description thereof.

Our invention relates to derricks for unloading coal, ore, &c., from vessels; and it consists in certain improvements in the same which look to the economizing of space, as will be described hereinafter.

In the drawings, Figure 1 is a side view of 15 our invention at work. Fig. 2 is a broken perspective view of the same, and Figs. 3 and 4 are details.

A is a permanent trestle, that may form part 20 of the coal-bin into which the coal from the vessel is to be unloaded. This trestle consists of two horses, each supporting an end of a shaft, a, and this shaft carries a pair of pinions, B B, and on each side of each pinion B we provide a swinging arm, and these arms 25 are arranged in pairs C C' C' C', their rear ends connected by shaft a, upon which they are adapted to turn loosely, and their outer or front ends being connected by a shaft, c, and between the arms of each pair we pass a member, 30 D, of our derrick D D.

To the under side of each member D we fix 35 a ratchet-bar, d, that when the derrick is in place rests upon a pinion, B, and as the pinions turn loosely on the shaft a they act as rollers, which, while they bear most of the weight 40 of the derrick, yield about their axes and permit the derrick to be slid up easily.

To lock the derrick after it has been adjusted, we provide each member with a plate, E, 45 having hooked teeth that project out to engage with the shaft c between the front ends of the arms C C' C' C', and as the teeth on plates E all slant downward they will ride under the shaft c when the derrick is being lifted, and will only engage it from above.

The members D are connected by any necessary number of cross-bars f. On their lower ends we provide the members D with plates F, that have straight teeth for engagement 50 with a bar, F', that may be adjusted up or down, so as to rest between any two of the

teeth, and form a stop for a car, H', by which the coal or ore bucket H is hoisted.

The lower end of our derrick, when in position for unloading a boat, is supported by a shaft or bar, G', that passes through suitable eyes on the under side of each member, and this bar passes through rings g on the upper cross-pieces of two horses, G G, which are designed to stand one on each side of the hatch 55 of the vessel to be unloaded, and as the shaft or bar G' fits loosely in the rings g, the distance between the two horses may be adjusted to suit the deck-room.

We usually provide the upper edge of the 60 members D with a rail or tramway to receive the flanged wheels of the carriage H', and we suspend the bucket H from an adjustable hanger, h, by a rope or chain, h', and suitable pulleys that travel up between the members 65 D, and we provide the bucket with a stop, i, that, when the bucket has been drawn up to the dumping elevation, strikes a swinging weight, K, and causes the bucket to lose its balance and dump its contents.

The rope or chain h', by which the bucket is 70 elevated, passes over a pulley, I, down under another pulley, I', and thence to any suitable power. After a boat has been unloaded by means of a block and tackle, T, in the rigging 75 of the boat, the boat end of the derrick may be lifted, and by a rope, T', hitched to its other or upper end the derrick may be drawn over on top of the bin, to remain there out of the way until it is again needed, and the horses 80 G G can be stored in any convenient place, so that my machine, when not in use, may be easily stored in such space as will be available for no other purpose.

In order to get beams of sufficient length 85 and strength for the members D, I make them of three thicknesses or layers of timber, w v w', the outer layers being doweled together to form one end of the member, and then mortised out, as at w', to receive the layer v between them, so that each member is composed of layers united by this system of splicing.

It is obvious that we may substitute rollers 90 for the pinions B B and leave off the ratchet plates or bars d without departing from the 100 spirit of our invention, though we much prefer to use pinions and ratchet-bars.

What we claim as our invention, and desire to secure by Letters Patent, is—

1. The combination of a shaft carrying rollers or pinions and supported on suitable trestle-work with a derrick adapted to slide upon said rollers or pinions, as set forth.
2. The derrick having toothed plates E, in combination with shaft *a*, arms C C' C', and shaft *c*, as set forth.
3. The combination of trestle-shaft *a*, pinions B B, arms C C' C', shaft *c*, and the toothed plates for engaging with shaft *c*, as set forth.
4. The permanent trestle and removable or portable horses of the sliding derrick and supporting-shafts, as set forth.

5. The combination, with the derrick, of plates F and stop-bar F', as set forth.

6. The carriage or car having an adjustable depending standard, in combination with the bucket having a stop or projection, *i*, the tackle for raising the bucket, and a swinging weight for dumping the bucket, as set forth.

In testimony that we claim the foregoing we have hereunto set our hands on this 29th day ²⁵ of September, 1882, in the presence of two witnesses.

FREDRICK C. STARKE.
PETER J. CROWLEY.
